UNITED STATES PATENT OFFICE.

MAX ROTHSCHILD, OF NEW YORK, N. Y., ASSIGNOR TO SUSQUEHANNA SILK MILLS, A CORPORATION OF NEW YORK.

DESIGN FOR A TEXTILE FABRIC.

Application filed July 20, 1926. Serial No. 18,426. Term of patent 3½ years.

To all whom it may concern:

Be it known that I, MAX ROTHSCHILD, a citizen of the United States of America, and resident of the city of New York, county of New York, and State of New York, have invented a new, original, and ornamental Design for a Textile Fabric, of which the following is a specification, reference being had to the accompanying drawing, forming part thereof.

The figure is a plan view of a textile fabric, illustrating my new and ornamental design.

I claim:

The ornamental design for a textile fabric as shown.

MAX ROTHSCHILD.
